[57] CLAIM

The ornamental design for a portable internal combustion power tool, as shown and described.

DESCRIPTION

FIG. 1 is a left side elevational view of a portable internal combustion power tool showing our new design; FIG. 2 is a right side elevational view thereof; FIG. 3 is a front elevational view thereof; FIG. 4 is a rear elevational view thereof; FIG. 5 is a top plan view thereof; FIG. 6 is a bottom plan view thereof; FIG. 7 is a left side elevational view of a second embodiment thereof; FIG. 8 is a right side elevational view thereof; FIG. 9 is a front elevational view thereof; FIG. 10 is a rear elevational view thereof; FIG. 11 is a top plan view thereof; FIG. 12 is a bottom plan view thereof; FIG. 13 is a left side elevational view of the engine thereof; FIG. 14 is a right side elevational view thereof; FIG. 15 is a front elevational view thereof; FIG. 16 is a rear elevational view thereof; FIG. 17 is a top plan view thereof; FIG. 18 is a bottom plan view thereof; FIG. 19 is a left side elevational view of the engine and handle thereof; FIG. 20 is a right side elevational view thereof; FIG. 21 is a front elevational view thereof; FIG. 22 is a rear elevational view thereof; FIG. 23 is a top plan view thereof; and FIG. 24 is a bottom plan view thereof.

The engine unit in FIGS. 13-18 and the engine unit and handle in FIGS. 19-24 are shown separate for clarity of illustration only.
